(57)

CLAIM

The ornamental design for a urine collection apparatus base, as shown and described.

DESCRIPTION

FIG. 1 is a front, top, perspective view of a urine collection apparatus base, according to a new design;
FIG. 2 is a rear elevational view thereof;
FIG. 3 is a front elevational view thereof;
FIG. 4 is a right side elevational view thereof;
FIG. 5 is a left side elevational view thereof;
FIG. 6 is a top plan view thereof; and,
FIG. 7 is a bottom plan view thereof.

The broken lines shown in the drawings depict portions of the urine collection apparatus base that form no part of the claimed design.
